UNITED STATES PATENT OFFICE.

RUDOLPH THIEM, OF HAMILTON, OHIO, ASSIGNOR TO THE SANFORD DAY IRON WORKS, OF KNOXVILLE, TENNESSEE.

DESIGN FOR A STOVE.

No. 37,933.

Specification for Design.

Patented April 3, 1906.

Application filed February 2, 1906. Serial No. 299,216. Term of patent 14 years.

To all whom it may concern:

Be it known that I, RUDOLPH THIEM, a citizen of the United States, residing at Hamilton, Butler county, Ohio, (post-office address No. 406 North D street, Hamilton, Ohio,) have invented a new and original Design for the Ornamentation of a Stove, of which the following is a specification, reference being had to the accompanying drawing.

The drawing is a perspective view of a

stove whose ornamentation embodies my new design.

I claim—

The ornamental design for a stove, as shown.

RUDOLPH THIEM.
